(57) CLAIM

The ornamental design for a practice hockey goaltender, as shown and described.

DESCRIPTION

A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

This application contains subject matter which is related to the subject matter of commonly owned and co-filed U.S. Utility patent application Ser. No. 14/658,961, entitled "Practice Hockey Goaltenders," by McMahon, Jr., which is hereby incorporated herein by reference in its entirety.

A portion of the disclosure of this patent document contains material which is a claim for copyright is made. The copyright owner has no objection to the facsimile reproduction by anyone of the patent document or the patent disclosure, as it appears in the Patent and Trademark Office patent file or records, but reserves all other copyright rights whatsoever.

FIG. 1 is a front perspective view of a practice hockey goaltender in accordance with the new design;

FIG. 2 is a rear perspective view of a thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top view thereof; and,

FIG. 8 is a bottom view thereof.

The broken lines in the figures are included for the purpose of illustrating portions of the practice hockey goal tender and its environment that form no part of the claimed design.
